CLAIM

The ornamental design for a beach umbrella stabilizer, as shown and described.

DESCRIPTION

FIG. 1 is a perspective view of a first embodiment of the beach umbrella stabilizer in accordance with the present invention;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a perspective view of a rendering of a second embodiment of the beach umbrella stabilizer in accordance with the present invention.

FIG. 9 is a front elevation view thereof;

FIG. 10 is a rear elevation view thereof;

FIG. 11 is a top plan view thereof;

FIG. 12 is a bottom plan view thereof;

FIG. 13 is a left side elevation view thereof;

FIG. 14 is a right side elevation view thereof;

FIG. 15 is a perspective view of a third embodiment of the beach umbrella stabilizer in accordance with the present invention.

FIG. 16 is a front elevation view thereof;

FIG. 17 is a rear elevation view thereof;

FIG. 18 is a top plan view thereof;

FIG. 19 is a bottom plan view thereof;

FIG. 20 is a left side elevation view thereof;

FIG. 21 is a right side elevation view thereof;

FIG. 22 is a perspective view of a rendering of a fourth embodiment of the beach umbrella stabilizer in accordance with the present invention.

FIG. 23 is a front elevation view thereof;

FIG. 24 is a rear elevation view thereof;

FIG. 25 is a top plan view thereof;

FIG. 26 is a bottom plan view thereof;

FIG. 27 is a left side elevation view thereof; and,

FIG. 28 is a right side elevation view thereof.

The broken lines in the drawings depict portions of the beach umbrella stabilizer that form no part of the claimed design.
